FIG. 5.

INVENTOR.
FRANZ LUNZ.

BY *J. Steward Schaff*
ATTORNEY.

UNITED STATES PATENT OFFICE.

FRANZ LUNZ, OF NEW YORK, N. Y., ASSIGNOR TO AERO TOY & MANUFACTURING CO., INC., OF NEW YORK, N. Y.

SPINNING TOY.

Application filed January 26, 1927. Serial No. 163,892.

The present invention consists in the provision of a spinning toy.

A particular object of this invention is to provide a spinning toy with a fire cracker 5 or cartridge.

A further object of this invention is to provide a spinning toy with a musical device.

A further object of this invention is to 10 provide an improved top or spinning toy that when the cord is unwound it causes the spinning device to go up and then down.

Other objects and advantages will appear in the following specification and the novel 15 features of the invention will be particularly pointed out in the appended claim.

In the drawing:

Fig. 1, represents a perspective view of the spinning toy.

Fig. 2, shows a view of the top or spinning device.

Fig. 3, shows a sectional view of the musical device set in the spinning toy.

Fig. 4, shows a view of the cartridge cap 25 on the stem.

Fig. 5, shows a modified form of stem.

In carrying out my invention, I provide a handle 1, which has an opening 2, and a slot 3. Through the opening 2, I insert the 30 top or spinning device 4, made out of wood or metal, attached to stem 6.

On the stem 6, I wind a cord 7, as shown, the end of the cord is inserted through the opening and drawn through the slot 3.

At the bottom of the stem 6, I insert a spike 8 with a flange 9, and projection 10.

On the projection 10, I fit a cartridge 11, partly filled with powder.

In the portion 4 of the spinning toy, I 40 provide an opening or two 12 wherein I insert a whistle or musical device 13, having a prong 14, which is caused to vibrate by the wind flowing through the opening 12.

In operation, the stem 6 of the spinning 45 toy is wound, and the cartridge 11 set on the projection 10 and the stem is inserted

in the opening 2 of the handle and the cord set through the slot 3. The handle is held in one hand and the cord drawn with the other hand. This causes the spinning toy to rise in the air and then come down with force. In so doing, it causes the cartridge to explode, and the toy keeps on spinning for quite awhile.

In Fig. 5, a modification of the stem is 55 shown. The stem 15, has an opening bored within indicated by number 16. A slot 17 is cut at the top of the boring 16 and within this slot I place a plate 18.

Within the boring 16, I place a vertical 60 pin 19, surrounded by a spring 20. The pin is capped by a plate 21. The spring is held against a shoulder 22 of the stem 15. The pin 19 projects beyond the stem 15 and terminates with a flange 23 and point 24.

In operation the pin 19 is drawn down, 65 against the spring and a paper cap 25 is inserted in the slot 17 between the metal plates 18 and 21 and the spring 20 holds the cap in place. When the toy is operated, 70 the point 24 of the pin 19 hits the ground and explodes the paper cap and the toy keeps on spinning.

What I claim is:

In a device of the class described, an elongated handle having a perforation therethrough at one end thereof and an open slot extending from the perforation to the edge of said handle, a spinning device comprising a body and an elongated stem, a cord wound around the stem, said stem with cord adapted to pass perpendicularly to the handle and through said perforation, the end of said cord adapted to drop into said slot, said slot then being covered by said body, 85 said stem having the lower end pointed, and a removable cartridge cap fitting frictionally over said pointed stem end.

Signed at New York, in the county of New York and State of New York, this 19th 90 day of January, A. D. 1927.

FRANZ LUNZ.
